UNITED STATES PATENT OFFICE

2,068,606

DOOR AND LATCH CONSTRUCTION

Hal W. McPherson, Cincinnati, Ohio, assignor to
General Motors Corporation, Dayton, Ohio, a
corporation of Delaware

Original application October 31, 1931, Serial No.
572,421. Patent No. 2,001,740, dated May 21,
1935. Divided and this application March 21,
1935, Serial No. 12,229

2 Claims. (Cl. 20—35)

This application is a division of my copending application Serial No. 572,421, now Patent No. 2,001,740, issued May 21, 1935, and is particularly directed to the modification shown in Figs. 4, 5 and 6 of the drawing of that patent and specifically described on pages 6 and 7 of the specification.

This invention relates to refrigerating apparatus and more particularly to latches for the doors of refrigerator cabinets for use with refrigerating apparatus.

Refrigerator cabinets are ordinarily provided with an insulated door provided with a relatively thick flange extending around the door which causes the door to project from the remainder of the front face of the cabinet about an inch or more. It has been customary to fasten the refrigerator door latch on the outside of the flanged door with the bolt mechanism projecting entirely above the face of the door. The keeper which is fastened to the stationary portion of the cabinet therefore must project several inches from the stationary portion of the cabinet. This also causes the latch and its handle to project a considerable distance from the face of the door. This projection becomes somewhat of a nuisance because it is often in the way. This particular construction also places a considerable strain upon the fastenings of the keeper since the cam surfaces of the keeper which are engaged by the bolt mechanism are a considerable distance from the fastening means of the keeper and thereby through this rather large moment arm a considerable force is made possible which tends to pull out the fastening screws of the keeper.

It is therefore an object of my invention to reduce the amount of projection of the latch mechanism and the keeper from the face of the cabinet and to reduce the strain upon the keeper.

Further objects and advantages of the present invention will be apparent from the following description, reference being had to the accompanying drawing, wherein a preferred form of the present invention is clearly shown.

In the drawing

Fig. 1 is a front view of a refrigerator cabinet showing my improved latch applied thereto;

Fig. 2 is a fragmentary sectional view of a portion of the refrigerator cabinet shown in Fig. 1 showing my improved latch mechanism and keeper, and

Fig. 3 is a sectional view along the line 3—3 of Fig. 2.

In Fig. 2 there is shown a fragmentary sectional view of a refrigerator door 54 including a

rectangular frame 50 and a facing member 51 fastened to the front side of the rectangular frame 50. Suitable insulation 52, such as cork, is provided within the rectangular frame 50 for insulating the door. A sheet metal covering 53, preferably provided with a suitable coating such as porcelain, is laid over the facing member 51 for covering the front surface of the door 54. This covering 53 is provided with a sunken groove 55 in which a tubular slideway 56 is fastened. Within the slideway 56 there is a cylindrical bolt 57 provided with a kerf at its outer end which receives a roller 58. The roller 58 engages a suitable keeper 59 which is fastened to the outer side of the door jamb 60. A suitable handle 61 is provided for retracting the bolt. This handle 61 is pivotally supported by means of the pin 62 upon a bracket 63 fastened by means of screws 64 to the outer face of the door and provided with upstanding ears 65 for receiving the pin 62. The bracket 63 is preferably brazed and sweated to the tubular slideway 56 to provide a unitary piece. The handle 61 has an operating arm 70 extending inwardly from the pivot pin 63 through a slot 67 in the outer portion of the tubular slideway 56 into a recess 69 provided for this purpose in the bolt 57. The operating arm 70 presses against the rear end of the recess 69 and retracts the bolt 57 and the roller 58 from engagement with the keeper 59 against the resilient force of the coil spring 71 which is provided between the inner end of the bolt 57 and the inner end of the tubular slideway 56.

An ornamental escutcheon plate 80 is provided for covering the latch mechanism so as to give the latch a pleasing appearance. By sinking the latch mechanism into the door, the amount of projection of the handle and the keeper is reduced because of the reduced moment arm, there is less strain upon the fastenings of the keeper.

While the form of embodiment of the invention as herein disclosed, constitutes a preferred form, it is to be understood that other forms might be adopted, all coming within the scope of the claims which follow.

What is claimed is as follows:

1. A door and a latch construction therefor, said door having a sheet metal outer face, said sheet metal outer face having a portion thereof depressed into the body of the door and forming a recess in the face of the door, said latch construction being secured to said door and fitting over the outer metallic face thereof, and said latch construction including mechanism having

a portion thereof in said recess to reduce the distance of projection of the latch from the door.

2. A door and a latch construction therefor, said door having a sheet metal covering forming the flat outer face thereof, said covering having a portion thereof depressed inwardly of the flat face of the door, said latch construction being

secured to said door and having a part thereof engaging the flat outer face thereof, and said latch construction also including mechanism having a part thereof disposed within said depression to reduce the distance of projection of the latch from the door. 5

HAL W. McPHERSON.
